SLOT CLOSER

Leo C. Luke, Evansville, Ind., assignor to International Door Company, Evansville, Ind., a corporation of Illinois

Application January 11, 1937, Serial No. 120,085

18 Claims. (Cl. 20—18)

My invention relates broadly to revolving doors and more particularly to an improved mechanism for automatically closing the longitudinally extending slot provided in the ceiling of a revolving door drum for allowing the shifting of the revolving door structure from a central position to a position adjacent one side of the revolving door with the revolving door wings in collapsed position.

10 One of the objects of my invention is to provide a simplified and efficient construction of slot closer for revolving door structures.

Another object of my invention is to provide a construction of slot closer for the slotted ceiling of revolving doors in which the slot closing plate is mounted for oscillatory movement subject to actuation by the shaft of the revolving door when the revolving door is shifted either to a remote position adjacent one side of the revolving door drum or to a position central of the revolving door drum.

Still another object of my invention is to provide a mounting for a slot closing plate for the slotted ceiling of a revolving door drum having means pivotally connected with opposite ends of the slot closing plate and pivotally supported with respect to the revolving door for shifting the slot closing plate to a position closing the slot in the slotted ceiling when the revolving door shaft reaches either of the limits of the path of travel thereof.

A further object of my invention is to provide a construction of pivoted cam means pivotally supporting a slot closing plate adjacent the slot in the slotted ceiling of a revolving door drum and operated by the shaft of a revolving door as the revolving door shaft reaches the limit of travel in either of the remote positions thereof for insuring the closing of the slot of the slotted opening when the revolving doors are either collapsed adjacent one side of the revolving door drum or journalled for normal rotative movement centrally of the revolving door drum.

Other and further objects of my invention relate in the arrangement of mounting means for a slot closer operative adjacent the slotted ceiling of a revolving door drum, as set forth more fully in the specification hereinafter following by reference to the accompanying drawings in which:

50 Figure 1 is an elevational view partially broken away and shown in section and illustrating a fragmentary portion of revolving door wings carried by the revolving door shaft in a normally central position with respect to the revolving door drum and with the slot closing plate in a

position closing the slot in the slotted ceiling; Fig. 2 is a fragmentary side elevational view partially in section and illustrating the revolving door shaft shifted to the limit of its position adjacent one side of the revolving door drum; Fig. 3 is a perspective view illustrating in spaced arrangement the several parts constituting the mounting means for the slot closing plate of my invention, and showing the slot closing plate broken away and foreshortened; Fig. 4 is a plan view of the slot closing plate of my invention illustrating the mounting means therefor with the revolving door shifted to a central position and the slot closed; Fig. 5 is a plan view illustrating the position of the slot closing plate when the revolving door is being shifted from the normal central position to a collapsed position adjacent one side of the revolving door drum; Fig. 6 is a plan view showing the position of the slot closing plate after the revolving door has been moved to a position adjacent one side of the revolving door drum with the slot closing plate closing the slot in the slotted ceiling of the revolving door drum; Fig. 7 is a transverse sectional view taken on line 7—7 of Fig. 4; Fig. 8 is a transverse sectional view taken on line 8—8 of Fig. 4; Fig. 9 is a transverse sectional view taken on line 9—9 of Fig. 4; Fig. 10 is a side elevational view partially in cross section and foreshortened for illustrating the slot closing plate in a position closing the slot in the slotted ceiling when the revolving door is shifted to a position adjacent one side of the drum of the revolving door; Fig. 11 is a longitudinal sectional view of the slot closing plate illustrated in Fig. 10 and showing in section the cam means which provide for the pivotal mounting of the slot closing plate adjacent opposite ends of the longitudinally extending slot in the ceiling of the revolving door drum; and Fig. 12 is a transverse sectional view taken on line 12—12 of Fig. 1 with parts shown partially in side elevation.

Referring to the drawings in more detail, reference character 1 designates the revolving door wings which are mounted by means of hangers 2 with respect to the revolving shaft 3. A trolley 4 is provided for supporting the revolving door shaft 3 in such a manner that rollers 5 on the frame 4 of the trolley may operate over the diametrically extending guide rails 6 for shifting the collapsed revolving door structure from the central rotative position to a position adjacent one side of the revolving door drum. The trolley 6 also carries the governor housing 7 for controlling the rotation of the revolving door wings.

The ceiling 8 of the revolving door drum is provided with a radially extending slot 12 through which the shaft 3 extends and along which the shaft 3 is adapted to be shifted in a vertical position in removing the shaft 3 from a central position to a collapsed position adjacent one side of the drum of the revolving door. The ceiling 8 is provided with a countersunk or recessed portion immediately surrounding the slot 12 for receiving the plate 10 which is slotted at 14 in a manner corresponding to the arrangement of the slot 12 in ceiling 8. Slotted plate 10 is secured to ceiling 8 by suitable means such as screws 11.

I provide brackets 15 and 25 supported on plate 10 adjacent opposite ends of slot 14 having portions directed toward each other and over the longitudinally extending slot 14. The brackets 15 and 25 are secured to plate 10 in any suitable manner. I have shown bracket 15 secured to plate 10 by means of rivets 16 passing through apertures 16a, as shown more clearly in Fig. 3. I have shown bracket 25 as provided with apertures 26a for the passage of rivets 26 therethrough.

25 The brackets 15 and 25 serve as mounting means for the slot closing plate 23 through the interposition of disc members 17 and 27. Disc member 17 is pivoted with respect to bracket 15 through the agency of the rivet member 18 which passes through aperture 18a in bracket 15 and aperture 18b in disc member 17.

The disc member 17 is provided with a radially extending notch 19 having a width slightly larger than the diameter of the vertically projecting portion 3 of the revolving door. The disc member 17 has a chordal cut-away portion 20 adjacent the outer extremity of the notch 19. The disc member 17 is provided with a member extending normal to the plane thereof in a position adjacent the periphery of the disc member and located on radial lines at an obtuse angle with respect to a medial radial line through the radially extending notch 19. The member 21 is headed on one side of the disc to provide a positive stop on the other side of the disc, as illustrated in Fig. 8, between disc member 17 and slot closer plate 23. Aperture 21b in slot closer plate 23 provides a passage for the pivot means 21 which projects from the headed end forming the stop. There is a notch 22 provided in bracket 15 for receiving the headed stop 21 when the slot closer plate 23 is in one of its extreme positions in the oscillatory path of travel of the slot closer plate 23.

55 The slot closer plate 23 is provided with a pair of peripherally extending ribs 24 for strengthening plate 23 and preventing flexing thereof as endwise forces are applied to the plate in effecting oscillatory movement thereof.

Bracket 25 provides pivotal mounting means 60 for disc member 27. A rivet 28 extends through aperture 28 in bracket 25 and through aperture 28b in disc member 27 providing rotative mounting means for disc member 27. A radially extending notch 29 is provided in disc member 65 27 of slightly larger dimension than the diameter of the upwardly projecting portion of shaft 3 and into which shaft 3 moves upon approach of shaft 3 to its limit of travel to the position adjacent one side of the revolving door drum.

70 Disc member 27 is provided with a chordal cut-away portion 30 adjacent notch 29 for co-action with shaft 3, as illustrated more fully in Figs. 4, 5, and 6. The disc member 27 carries a member 31 adjacent the periphery of the disc 75 and on a radial line extending at an obtuse angle

with respect to a medial line through radially extending notch 29. Member 31 provides a stop on the upper face of the disc member 27 and a pivot means projecting below disc member 27 as represented by pivot member 31a between disc member 27 and slot closer plate 23. The pivot member 31a passes through aperture 31b in slot closer plate 23. The disc member 27 is freely rotatable about pivot 28 and plate member 23 is adapted for oscillatory movement about pivot 10 member 31 as a center.

Bracket 25 is notched at 32 for receiving stop 31 and limiting the oscillatory movement of plate 23.

The diametrically extending rails 6 are integrally formed from the channel shaped member 33 which extends diametrically across the top of the revolving door drum. The lower portion of channel 33 is slotted at 34 in alignment with the slots 12 in ceiling 8 and 14 in plate 10 for permitting longitudinal movement of the upper portion 3 of the shaft of the revolving door.

20 The slot closer plate 23 is capable of oscillatory movement within limits determined by the abutment of limiting stop 21 in notch 22 in bracket 15 on the one hand and by the abutment of stop 31 in notch 32 in bracket 25 on the other hand. In addition to this arrangement of limiting stops, I provide limiting stops 35 and 36 30 against which the peripheral edge of slot closer plate 23 abuts. The limiting stops 35 and 36 are provided with apertures 35b and 36b through which sets of screws or other securing means 35a and 36a extend for securing the stops 35 and 36 in position with respect to plate 10. 35

The trolley 4 is limited in movement to a position adjacent one side of the drum of the revolving door by means of the stop 37 and adjustable screw 38 which extends therethrough.

The slot closer of my invention has proven 40 highly effective in manufacture, assembly and production. The revolving door shaft exerts a force against the cam shaped chordal cut-away and notched portions of the disc members 17 and 27 which insures a positive opening of the slot 45 in the ceiling of the revolving door drum from a normally closed position to allow shifting of the revolving door structure from a central position to a position adjacent one side of the drum of the revolving door with an accompanying 50 positive closing of the open slot when the revolving door shaft reaches the limit of movement thereof adjacent the side of the revolving door drum. Likewise, when the revolving door is returned to normal position, the disc members 55 contact to automatically open the normally closed slot and automatically close the slot after the revolving door has been restored to its normal central position.

While I have described my invention in one 60 of its preferred embodiments, I desire that it be understood that modifications may be made and I intend no limitations upon my invention other than may be imposed by the scope of the appended claims.

What I claim as new and desire to secure by Letters Patent of the United States, is as follows:

1. A slot closer for the longitudinally extending slot in the ceiling of a revolving door drum through which the revolving door shaft extends, comprising supports adjacent opposite ends of the slotted portion of the ceiling, a slot closing plate, and means carried by said supports for suspending said slot closing plate for oscilla- 75

tory movement for opening or closing the slotted portion of the ceiling, said means being engaged and actuated by the shaft of the revolving door.

2. A slot closer comprising in combination with a slotted plate providing a longitudinally extending path of travel for a shaft member extending therethrough, a slot closing plate, supports carried by said slotted plate, and means for suspending said slot closing plate in said supports and operative in an oscillatory path, said means being engaged and actuated by said shaft member in the shifting of the shaft member in said slotted plate for opening or closing the slot in the slotted plate.

15 3. A slot closer for the longitudinally extending slot in the ceiling of a revolving door drum through which the shaft of the revolving door is shiftable, comprising in combination with a slotted ceiling plate, supports adjacent opposite 20 ends of the slot in the slotted ceiling plate, a slot closing plate, and rotatable means interconnecting said supports and said slot closing plate for allowing swinging movement of said slot closing plate to cover or uncover the slot in said slotted 25 ceiling plate, said rotatable means being engaged and actuated by said shaft.

4. A slot closer for the longitudinally extending slot in the ceiling of a revolving door drum through which the shaft of the revolving door 30 is shiftable, comprising in combination with a slotted ceiling plate, supports adjacent opposite ends of the slot in the slotted ceiling plate, a slot closing plate, a disc member journaled in each of said supports, and a pivotal connection 35 between said disc members and said slot closing plate, said disc members being engageable by said shaft for moving said slot closing plate for covering or uncovering the slot in the slotted ceiling plate, according to the shifting of the 40 revolving door shaft in the longitudinally extending slot.

5. A slot closer for the longitudinally extending slot in the ceiling of a revolving door drum through which the shaft of the revolving door is 45 shiftable, comprising in combination with a slotted ceiling plate, supports adjacent opposite ends of the slot in the slotted ceiling plate, a slot closing plate, a disc member pivotally mounted in each of said supports, a pivotal suspension 50 for said slot closing plate between said disc members, and means for effecting an engagement between said shaft and said disc members as said shaft shifts to the limits of travel thereof in the slotted ceiling plate for covering and 55 uncovering the slot in said slotted ceiling plate.

6. A slot closer for the longitudinally extending slot in the ceiling of a revolving door drum through which the shaft of the revolving door is shiftable, comprising in combination with a 60 slotted ceiling plate, supports adjacent opposite ends of the slot in the slotted ceiling plate, a slot closing plate, and means for suspending said slot closing plate in said supports engageable by said shaft for moving said slot closing plate for 65 covering or uncovering the slot according to the shifting of said shaft from one limiting position to another.

7. A device of the character described comprising in combination, a member formed with a relatively long narrow slot, a shaft extending 70 through and shiftable along said slot, a slot closing plate member swingable from a position wholly covering the slot to a position wholly uncovering the slot, supports carried by said 75 member, rotary devices journaled in said sup-

ports, and a pivotal connection between said rotary devices and said slot closing plate, said rotary devices being engageable by said shaft adjacent opposite ends of said slot for moving said slot closing plate for opening or closing the slot in said member. 5

8. A device of the character described comprising in combination, a member formed with a relatively long narrow slot, a shaft extending through and shiftable along said slot, a support 10 carried by said member adjacent each end of the slot, a rotatable member journaled in each of said supports, each of said members having a radially disposed recess therein engageable with the shaft as the shaft is shifted to either end of 15 the slot, a slot closing plate and a pivotal connection between said slot closing plate and each of said members whereby said slot closing plate is adapted to be swung into a position covering or uncovering said slot. 20

9. A device of the character described comprising in combination, a member formed with a relatively long narrow slot, a shaft extending through and shiftable along said slot, a support 25 carried by said member adjacent each end of the slot, a rotatable member journaled in each of said supports, each of said members having a radially disposed recess therein engageable with the shaft as the shaft is shifted to either end of 30 the slot, a slot closing plate and a pivotal connection between said slot closing plate and each of said members whereby said slot closing plate is adapted to be swung into a position covering or uncovering said slot, and a limiting stop carried by each of said rotatable members and adapted 35 to alternately abut respectively with the said supports when said slot closing plate is shifted to either of the two positions thereof in which the slot in said first mentioned member is closed. 35

10. A device of the character described comprising in combination, a member formed with a relatively long narrow slot, a shaft extending through and shiftable along said slot, a support 40 carried by said member adjacent each end of the slot, a rotatable member journaled in each of said supports, each of said members having a radially disposed recess therein engageable with the shaft as the shaft is shifted to either end of 45 the slot, a slot closing plate and a pivotal connection between said slot closing plate and each of said members whereby said slot closing plate is adapted to be swung into a position covering or uncovering said slot, and a limiting stop carried by each of said rotatable members and coacting with the respective supports for limiting the path 50 of movement of said slot closing plate. 55

11. A device of the character described comprising in combination, a member formed with a relatively long narrow slot, a shaft extending through and shiftable along said slot, a support 60 carried by said member adjacent each end of the slot, a rotatable member journaled in each of said supports, each of said members having a radially disposed recess therein engageable with the shaft as the shaft is shifted to either end of 65 the slot, a slot closing plate and a pivotal connection between said slot closing plate and each of said members whereby said slot closing plate is adapted to be swung into a position covering or uncovering said slot, and abutments carried 70 by said first mentioned member and by said rotatable members for limiting the path of travel of said slot closing plate. 75

12. A device of the character described comprising in combination, a member formed with 75

a relatively long narrow slot, a shaft extending through and shiftable along said slot, a support carried by said member adjacent each end of the slot, a rotatable member journaled in each of said supports, each of said members having a radially disposed recess therein engageable with the shaft as the shaft is shifted to either end of the slot, a slot closing plate and a pivotal connection between said slot closing plate and each 10 of said members whereby said slot closing plate is adapted to be swung into a position covering or uncovering said slot, said rotatable members each having a limiting stop thereon coacting with the respective supports and said first mentioned 15 member having limiting stops thereon coacting with one of the peripheral edges of said slot closing plate, said stops coacting to form abutments determining the extent of travel of said slot closing plate.

20 13. A device of the character described comprising in combination, a member formed with a relatively long narrow slot, a shaft extending through and shiftable along said slot, a support carried by said member adjacent each end of 25 the slot, an angularly shiftable member journaled in each of said supports, a cam shaped deformation in each of said shiftable members engageable with said shaft, a slot closing plate and a pivotal connection between said slot closing 30 plate and each of said angularly shiftable members whereby movement of the shaft in engagement with the cam shaped deformations in said angularly shiftable members effects a movement of said slot closing plate with respect to the long 35 narrow slot.

14. A device of the character described comprising in combination, a member formed with a relatively long narrow slot, a shaft extending through and shiftable along said slot, a support 40 carried by said member adjacent each end of the slot, an angularly shiftable member journaled in each of said supports, a cam shaped deformation in each of said shiftable members engageable with said shaft, a slot closing plate and a pivotal 45 connection between said slot closing plate and each of said angularly shiftable members whereby movement of the shaft in engagement with the cam shaped deformations in said angularly shiftable members effects a movement of said 50 slot closing plate with respect to the long narrow slot, and a stop carried by each of said

angularly shiftable members in a position removed from the cam shaped deformation therein through the angular distance of an obtuse angle.

15. In combination, a member formed with a relatively long and narrow closed slot, a shaft 5 extending through and shiftable along said slot, a slot closing plate and means connected with said plate and actuated by said shaft in moving into and out of the limiting positions thereof in said slot for respectively closing and opening said slot by said plate, said means being operative to move the same portion of said plate to close said slot with the shaft in either limiting position thereof in said slot.

16. In combination, a member formed with a 15 relatively long and narrow closed slot, a shaft extending through and shiftable along said slot, a slot closing plate, and means connected with said plate and actuated by said shaft in moving into and out of the limiting positions thereof in 20 said slot for respectively closing and opening said slot by said plate, said means being operative to move said plate in an arc for opening and closing said slot as said shaft is moved from one limiting position to the other in said slot. 25

17. In combination, a member formed with a relatively long and narrow closed slot, a shaft extending through and shiftable along said slot, a slot closing plate, and means connected with said plate and actuated by said shaft in moving 30 into and out of the limiting positions thereof in said slot for respectively closing and opening said slot by said plate, said means being operative to move said plate with a component of motion normal to said slot substantially equal to the 35 width of said slot.

18. In combination, a member formed with a relatively long and narrow closed slot, a shaft extending through and shiftable along said slot, a slot closing plate, and means connected with 40 said plate and actuated by said shaft in moving into and out of the limiting positions thereof in said slot for respectively closing and opening said slot by said plate, said means being operative to move said plate with a component of motion 45 normal to said slot substantially equal to the width of said slot and a component of motion parallel to said slot at least equal to the thickness of said shaft.

LEO C. LUKE. 50
